UNITED STATES PATENT OFFICE.

LELAND H. PLATT, OF LOS ANGELES, CALIFORNIA.

FRUIT-BOX-COVER PRESS.

Application filed March 18, 1925. Serial No. 16,310.

This invention relates to fruit packing presses and more particularly to deciduous fruits that are packed in boxes or crates that are overfilled and bulge the slats forming the top and bottom, and are also usually provided with a cleat at each end of the top and bottom, and the principal object is to provide a press that will have a greater range of movement and adjustment in relation to the different size boxes used, both in length and height.

It is also an object to provide a box press in which a gradually increasing pressure may be obtained with a shorter fulcrum and a link movement, giving the greatest ease and less manual movement of the operator, and the lid holder held securely in position while the lid and cleats are being nailed, with the equalized bulging of the bottom provided for by a curved box seat.

It is a further object to provide a back fruit guard so that the operator will not have to spend time trying to prevent fruit from being pressed out in the rear, this also acting to support an adjustable box stop to properly register the overfilled box under the cover pressing member.

In the drawing accompanying this specification

Figure 1, is a front elevation of the press in the receptive position for a box, the front end of the operating lever being broken away in a line flush with the front of the seat support.

Fig. 2 is a vertical side elevation of Fig. 1, a portion of the side frame being broken away to better show the link for obtaining the greater range and pressure, the dotted line showing the lower position, and

Fig. 3 is a plan view enlarged of the curved lid member, to clearly show how the lid contact may be adjusted for different lengths of slats, and bring the pressure close to the ends, the straight edge also acting as a gauge for the cleats.

More specifically in the drawings numerals are used to designate the indicated parts of the structure, 5 indicating the main uprights of the frame, preferably formed of angle iron, these being supported and held in vertical position by suitable angle iron braces, and spaced apart in parallel relation to support on their inner faces the U shaped guideways 6-6 within which slides the sliding frame 7 provided with the forwardly projecting arms 8-8 preferably

formed as shown with "goose necks" to allow a greater range of movement of the lid contacting member supported thereon and carry the same below the upper edge of 60 the fruit back guard 9.

The frame 7 is resiliently supported by the battery of coiled springs 10-10 though counter weights may be used to hold the frame up and return it to this position in opposition to the depressing movement of the foot lever 11, pivotally supported in the rear of the uprights 5-5 on a supplementary frame 12 by a pin 14, this lever being preferably formed of two lengths of strap metal that are secured together face to face for the greater part of their length, but are spaced apart at the forward end to straddle the arcuate rack 15, embrace the pivoted pawl 16, adapted to engage the teeth of the rack, and secure, at the end, the foot pedal 17 preferably formed of T angle iron.

Secured rigidly to the lever forward of its pivoted end are the castings, 18-18 adapted to extend above the lever and embrace the slotted portion of the arcuate link 19, and through the arcuate formed slot therein projects the pin 20, its ends secured in suitable bores in the casting, and preferably provided with anti friction sleeve or sleeves to roll in the slot.

This link 19 is pivoted in a fixed position on the auxiliary frame 12 by a pin 13, its oppositely disposed end being also provided with a bore to receive the pivot pin 21 secured in the open end of the yoke 22, the upper end of this yoke being provided with a threaded bore to receive the threaded end of the eye bolt 23, adapted to be hooked over the hook 24 secured in the lower cross bar of the frame 7, so that adjustment is provided for the throw of the frame; a suitable lock nut being provided to lock the adjustment.

Secured to the horizontally disposed portion of the arms 8 are the upwardly bowed cross bars 25-25 so spaced as to be of less distance apart than the width of any box and of less length than any box used on the press, and secured under these and inside of bars 8-8 are the flat bars 26-26 that form a sliding support for the sliding bars 27-27 secured at their outer ends to the lid contacting plates 28-28 by suitable fastenings to leave a smooth under surface, these fastenings also serving to secure a cross slide bar 29 over each plate 28 so spaced therefrom by suitable spacers at each end as to stiffen

the plates 28 and permit the ends of bars 25 to slide between and in parallel relation to the bars 27, as shown by full and dotted lines on the right side of Fig. 3.

Secured in the bars 26 are counter sunk bolts 30 which project upwardly through the slots in the two forward bars 27, and are provided with thumb nuts 31, so that the outer slidable elements may be fixed in any adjustable position to accommodate different length boxes, the length of the bars 28 being greater or equal to the rarely varying width of fruit boxes.

Below the pressing elements and the fruit guard 9 is provided a curved box seat 33, of the adjustable type disclosed in patent granted to J. H. Platt for crate presses numbered 1,345,878 of July 6, 1920, consisting of the pivoted links 34 hinged in the seat frame 35 and operated by handles 36, so that by elevating the box seat by lifting the bars, shallower boxes will be accommodated as necessary.

By the employment of the arcuate link a greater leverage is exerted in a more direct line at the final stage of the required pressure on the fruit by the lid in its contact with the overfilled box, as well as a greater range or "throw" as indicated by lines 40, and the bowed form of the bars 25 allow of the bulging of the lids forming the cover without breakage, delay or loss of material.

In the operation of the press the plates 28 are slid out or in until their outer edges register just within the nailing line of the cover and preferably within such a distance from the end of the box that they act as a gauge for the placing of the cleats used to reinforce this type of packing box, these cleats having a shelf provided on either side at 56, a stripper box clamp 37 being shown that may be shifted from one shelf to the other, depending on the right or left handed use by the operator, the usual rack for the lids being provided by frame 38 and bars 39.

I claim:

1. In a fruit press of the class described, the combination of a supporting frame provided with guideways, a frame provided with a pressing member adapted to be operated in said guideways, an opposed box seat mounted on said frame, a lever hinged to said supporting frame, and a pivoted arcuate link interposed between said frame provided with a pressing member and said lever whereby the pressure exerted in the opera-

tion of said lever is varied as to the amount of pressure produced by said pressing member.

60

2. A fruit press of the class described, combining a supporting frame provided with guideways, a sliding frame resiliently supported in said guideways, an opposed box seat, an operating lever, an arcuate link movably connected to said lever, means to pivot said link to said supporting frame, and means to connect said link to said sliding frame whereby movement of said lever will move said sliding frame in opposition to said box seat.

65

3. A fruit box cover press comprising a supporting frame provided with a sliding frame carrying a pressing member supporting adjustable lid contacting members and an opposed box seat, an operating lever for said sliding frame, and a pivoted link connecting said lever and said sliding frame whereby the relative movement will be varied to give greater pressure toward the termination of the movement.

75

4. In a fruit box cover press, the combination of a movable frame supported adjacent a box seat, a box seat, arms secured to said movable frame and extending transversely over said box seat, lateral supporting plates secured to said transverse arms, laterally movable transverse lid contacting plates adapted to slide in relation to said lateral supporting plates and extending outwardly therefrom, slide bars secured to said lid contacting plates and adapted to embrace said lateral supporting plates, arms extending inwardly from said lid contacting plates and secured thereto and to said slide bars, short transverse bars secured to said lateral supporting plates to support said arms, and means to lock said arms in relation to said short transverse bars.

80

5. In a fruit box cover press, the combination of a movable frame supported adjacent a box seat, a box seat, arms secured to said movable frame extending transversely over said box seat, lateral supporting plates secured to said transverse arms transverse lid contacting plates adjacent said transverse arms, adapted to slide on said lateral supporting plates slotted arms connected to said lid contacting plates slidably mounted in relation to said transverse arms, and means to lock said slotted arms in relation to said lateral and transverse arms.
